UNITED STATES PATENT OFFICE.

ANDREW HERMAN, OF CHEYENNE, WYOMING.

FILING HAND-FLANGE.

SPECIFICATION forming part of Letters Patent No. 624,485, dated May 9, 1899.

Application filed August 6, 1898. Serial No. 687,997. (No model.)

To all whom it may concern:

Be it known that I, ANDREW HERMAN, a resident of Cheyenne, county of Laramie, State of Wyoming, have invented an Improvement in Filing Hand-Flanges, of which the following is a specification.

This invention contemplates certain new and useful improvements in filing hand-flanges; and it has for its object the production of a simple and efficient tool of this nature whereby the soles of boots, shoes, and the like may be so filed near the edges thereof as to give the same a finished appearance when ready for the market.

15 The invention will be hereinafter fully set forth, and particularly pointed out in the claims.

In the accompanying drawings, Figure 1 is a side elevation illustrating my invention. 20 Fig. 2 is a longitudinal sectional view thereof. Figs. 3 and 4 are details.

Referring to the drawings, A designates a head or carrier having an upper reduced portion *a* fitting snugly within a corresponding recess in handle *a'*. The files or other scraping members B are flat and of approximately rectangular shape in cross-section, the top and bottom surfaces *b* thereof being preferably provided with the usual cutting or rasping surfaces. Said files are firmly held against the lower flat surface *b'* of carrier A by a clamp or member C of approximately inverted-T shape, said clamp or member having a central shank or tongue *b*², designed to keep the files separated and two lateral wings or extensions *b*³, upon which said files are designed to rest. The wings of the clamp are firmly bound against said files by means of a binding-screw *b*⁴, passed through a hole or opening *b*⁵ in clamp C and working in a threaded recess *b*⁶ of carrier A, which registers with said hole or opening.

In practice the boot or shoe to be operated upon is inverted, and the tool is brought in contact therewith by placing one of the flat sides of clamp C against the outer edge of the sole, thus bringing one or the other of the files directly against the surface of the leather.

The tool is then moved back and forth, using the edge of the sole for a guide until the desired finish is obtained.

The advantages of my invention are at once apparent from what has been said. It will be particularly observed that the files are rigidly held between the clamp and the carrier while in use and at the same time bear against the sides of said shank, and yet the construction is such that they can be readily and easily interchanged or new ones substituted at will.

A further advantage possessed by my improved filing hand-flange lies in the fact that the same is extremely simple and inexpensive, and being composed of but few parts is not liable to readily get out of order or become deranged.

I claim as my invention—

1. A tool for finishing boots and shoes, comprising a carrier, a clamp adjustably secured thereto and having a central shank, and scraping devices held between said carrier, and said clamp, and separated from each other by said shank, as set forth.

2. A tool for finishing boots and shoes, comprising a carrier, an elongated clamp having a central shank and lateral wings, said wings having straight edges forming guides, scraping devices located between said wings and said carrier, and means for securing said clamp to said carrier, substantially as set forth.

3. A tool for finishing boots and shoes, comprising a carrier having a threaded recess therein, a clamp having a hole or opening designed to register with said recess, said clamp also having a central shank and lateral wings, scraping devices located between said wings and said carrier, and a binding-screw passed through the hole or opening of said clamp and working in the recess of said carrier, substantially as set forth.

ANDREW HERMAN.
